WALL CLEANING AND SIZING APPARATUS.

1,255,695.

Specification of Letters Patent.

Patented Feb. 5, 1918.

Application filed June 9, 1917. Serial No. 173,832.

To all whom it may concern:

- Be it known that I, ALFRED BLUMENTHAL, a citizen of the United States, and a resident of the city of New York, borough of the Bronx, in the county of Bronx and State of New York, have invented a new and Improved Wall Cleaning and Sizing Apparatus, of which the following is a full, clear, and exact description.
10. The invention relates to fountain brushes, and its object is to provide a new and improved wall cleaning and sizing apparatus more especially designed for quickly and effectively renovating slightly soiled rooms.
15. In order to accomplish the desired result, use is made of a handled reservoir adapted to be filled with a liquid and provided with an opening extending the entire length of the reservoir, and an applying member fitting into the said opening and having an inner portion extending into the reservoir and having an outer portion projecting from the reservoir, the said applying member comprising a receptacle and a fabric covering inclosing the receptacle.
20. A practical embodiment of the invention is represented in the accompanying drawings forming a part of this specification, in which similar characters of reference indicate corresponding parts in all the views.
25. Figure 1 is a perspective view of the wall cleaning and sizing apparatus;
30. Fig. 2 is an enlarged sectional side elevation of the same; and
35. Fig. 3 is a face view partly in section of a portion of the applying member.
- The reservoir 10 is adapted to contain water, calcimine or a suitable liquid 11, and from the back of the reservoir 10 projects a socket 12 which can be used as a handle to manipulate the apparatus, as hereinafter more fully explained. A stick 13 may be inserted in the socket 12 for conveniently using the apparatus in rooms having high walls. The reservoir 10 is provided at its under side with a depending socket 14 extending the entire length of the reservoir 10. Into the socket 14 is removably fitted an applying member 15 for applying the liquid 11 to a wall or ceiling. The applying member 15 consists of a receptacle 16 of sheet metal or similar rigid material, with the walls of the receptacle perforated, as plainly indicated in Figs. 2 and 3. The receptacle 16 is inclosed by a covering 17 of wick ma-
- terial, felt or other similar fabric. The applying member 15 is preferably rectangular in cross section, and the ends of the receptacle 16 are provided with outwardly extending lugs 18 located approximately at 60 the middle of the end to limit the inward movement of the applying member when inserting the same in the socket 14.
- By reference to Fig. 2 it will be noticed that the applying member is so proportioned relative to the socket 14 that a portion of the applying member extends into the reservoir 10 and a portion projects from the socket 14. By the arrangement described the liquid contained in the reservoir 10 can readily pass through the inner portion of the fabric covering 17 into the receptacle 16 by way of the perforations thereof, and this liquid can also pass through the perforations into the fabric material 17 of the outer portion of the applying member 15 to saturate such fabric material and thus allow of conveniently applying the liquid to a wall to be washed, calcimined or otherwise renovated.
- It is understood that in using the apparatus the operation draws the outer portions of the applying member 15 over the surface to be cleaned or renovated. In case the wall or other surface is to be washed, the reservoir 10 is filled with water, and in drawing the outer portion of the applying member over the surface the saturated covering applies the water to the wall thus washing off any dirt that may be on the surface. In a 90 similar manner when it is desired to calcimine a surface, the reservoir 10 is filled with the calcimine and the apparatus is then used as above described, to cause the fabric material to apply the calcimine to the surface.
- After washing the wall or similar surface with water, as above explained it is desirable to dry the same and for this purpose use is made of a wiper 20, preferably in the form of a strip of rubber, held between two 100 metallic strips 21 and 22 and fastened by bolts 23 to a flange 24 projecting from the top of the reservoir 10 and doubled up to render the flange exceedingly strong and durable. The strips 21 and 22 are preferably narrower than the strip of rubber 20, to permit of using either edge of the rubber strip until worn down to the edges of the metallic strips 21 and 22. It is understood that when the outer edge of the rubber strip 110

20 has been worn down then the wiper is reversed to permit of using the other edge of the rubber strip.

It will be noticed that the apparatus is 5 very simple in construction and can be readily used by an unskilled operator both for washing walls and ceilings or calcimining the same, as the case may be.

It will also be noticed that the applying 10 member 15 can be readily removed from the reservoir 10 to permit of filling the latter with the water, calcimine or other liquid, and in case the outer portion of the fabric covering 17 has been worn down the applying member can be reversely inserted in the socket 14. In case the entire covering 17 15 has been worn down it can be removed and replaced on the receptacle 16 by a new one.

By reference to the drawings it will be 20 noticed that the front of the reservoir 10 is perfectly flat to enable the user to readily wash, dry or size walls or ceilings with the applying member 15 and without danger of scratching or otherwise injuring the surface 25 of the wall while operating on the ceiling, or the surface of the ceiling while working on the wall.

Having thus described my invention, I 20 claim as new and desire to secure by Letters 30 Patent:

1. A wall cleaning and sizing apparatus, comprising a handled reservoir adapted to be filled with a liquid and provided with an opening extending the entire length of the 35 reservoir, and an applying member fitting

into the said opening and having an inner portion extending into the reservoir and having an outer portion projecting from the reservoir, the said applying member comprising a perforated receptacle and a fabric 40 covering inclosing the receptacle.

2. A wall cleaning and sizing apparatus, comprising a handled reservoir adapted to be filled with a liquid and provided with an opening extending the entire length of the 45 reservoir, and an applying member fitting into the said opening and having an inner portion extending into the reservoir and having an outer portion projecting from the reservoir, the said applying member comprising a tubular perforate receptacle of a 50 rigid material and a covering of a fabric material inclosing the said receptacle.

3. A wall cleaning and sizing apparatus, comprising a handled reservoir adapted to be filled with a liquid and provided with an opening extending the entire length of the reservoir, and an applying member fitting 55 into the said opening and having an inner portion extending into the reservoir and having an outer portion projecting from the reservoir, the said applying member comprising a tubular perforate receptacle of a rigid material and a covering of a fabric 60 material inclosing the said receptacle, the said receptacle having outwardly projecting lugs limiting the inward movement of the applying member when inserting the same into the opening of the reservoir.

ALFRED BLUMENTHAL.
